UNITED STATES PATENT OFFICE.

CHARLES EDMUND KELLS, JR., OF NEW ORLEANS, LOUISIANA.

ELECTRIC BELL.

SPECIFICATION forming part of Letters Patent No. 313,941, dated March 17, 1885.

Application filed May 31, 1884. (No model.)

To all whom it may concern:

Be it known that I, CHARLES EDMUND KELLS, Jr., of New Orleans, in the parish of Orleans and State of Louisiana, have invented 5 certain new and useful Improvements in Electric Bells, of which the following is a specification.

My invention is especially designed for an alarm-bell, and relates to that class of instruments in which a local or bell-ringing circuit is completed by the closing of the main circuit, or the circuit that connects with the windows, doors, or other places with which the alarm is connected.

15 The accompanying drawing is a plan view of my improved alarm-bell, and shows diagrammatically the arrangement of the electric circuits.

The armature D of the electro-magnet C is 20 carried by a spring, E, secured to the frame or supporting-plate A at F. The opposite or free end of this spring normally rests against an adjustable contact-screw, a, which works in a metallic post, b. The hammer G 25 of the bell B is carried by or constitutes a prolongation of the armature D, as shown. A circuit-changer, rod, or contact-bar H is eccentrically pivoted to the plate A at c, and normally rests by gravity upon an insulated 30 stop, d. The outer end of the rod H, when turned to the left, (as indicated by dotted lines,) falls by gravity upon and makes electrical contact with a stud, e. The lower and shorter end of the rod H is normally in contact with 35 or in close proximity to the armature D, as shown by the full lines in the drawing. When the armature is attracted, the rod is turned to the left, as indicated by dotted lines, and falls against the contact-stop e.

40 K L M are binding-posts for the circuit-connections.

The battery-connections are as follows: The line runs from one pole of the battery N to the binding-post L, to the spring E, contact-screw a, coils of electro-magnet, binding-post 45 M, and thence through a switch, RS, to the opposite pole of the battery. Between the switch RS and the binding-post M the doors, windows, or other places T are connected, 50 each door or window T being included in a separate loop of the circuit, and there may be

any desired number, as is well understood. When the instrument is set to give the alarm, the contact-bar H is in the normal position indicated by the full lines in the drawing. 55 The circuit above described, which is indicated by the letter x, will therefore be completed at every point except at the door or window T. The arrangement there is such that any movement will close the circuit. The 60 armature D will be attracted, a stroke will be given on the bell, and the contact-bar H will be thrown into the position indicated by dotted lines. This completes a local ringing circuit, (indicated by y.) It runs from one pole 65 of the battery N through the switch RS to the binding-post K; thence to the contact-stop e, contact-bar H, wire y, to the binding-post M; thence through the coils of the electro-magnet to the screw-contact a; thence 70 by armature-spring E to the binding-post L and opposite pole of the battery. The bell will therefore automatically continue ringing, even though the circuit at T may again be broken, because it will be perceived that 75 the circuit y is now entirely independent of that part of the circuit x between the binding-post M and the switch RS. Any one tampering with the door or window T cannot therefore stop the ringing of the alarm. 80 The bar H may readily be restored to its normal position by means of a pivoted rod, I, which vibrates between two stop-pins, and is operated to throw the bar H back into position by means of a cord, J, as clearly shown 85 in the drawing.

RS represents any ordinary switch by means of which the apparatus may be thrown out of operation during the hours of the day when it is not needed. This may be done by 90 opening the local ringing circuit y at the switch. The main circuit x may also be opened at the switch; or the circuit-completing device at the doors or windows may be of such a character that they may be thrown out of 95 operation when desired.

I claim as my invention—

1. The main circuit, the local ringing circuit, the electro-magnet, the vibrating armature of said magnet, carrying the bell-hammer, 100 the vertical pivoted gravity circuit-completing bar, arranged, when in its normal position,

with its lower end in contact with or in close proximity to said armature, a stop, d' , against which said bar normally lies, and the contact-stop e , against which the pivoted bar is thrown to complete the ringing circuit when the armature is attracted.

2. The combination of the electro-magnet, its armature, the main and local circuits, the vertical pivoted gravity circuit-completing bar, arranged with its lower end in a position to be struck by the armature when the arma-

ture is attracted, the stop d' , the contact e , and the pivoted rod I, which serves to throw the gravity-bar back upon its normal supporting stop d' .

In testimony whereof I have hereunto subscribed my name.

CHARLES EDMUND KELLS, JR.
